UNITED STATES PATENT OFFICE.

CONRAD T. NEITZEL, OF DALLAS, TEXAS.

WELL-TESTING TOOL.

REISSUED

Application filed February 14, 1927. Serial No. 167,910.

This invention relates to rotary well tools and equipment and it has particular reference to a new and useful tool designed for the purpose of obtaining tests of sands and mineral strata principally in drilling oil wells, and its chief object resides in the provision of equipment by which to determine the nature and characteristics of the strata encountered, and whether or not it possesses such value as to justify the installation of casing.

The invention further comprehends a tool of the character designated which may be substituted for the drill bit, in cases where sand tests are required, and lowered into the hole without the usual waste of time and otherwise expensive procedure of setting up casing, the latter not infrequently proving to be of no value whatever.

Another object of the invention resides in the provision of a double seat, their joint function being positively effective in shutting off all fluid tending to rise above the tool, and forcing the same to pass through the tool into the drill pipe, there to be trapped and used as a sample.

Yet another object of the invention resides in its apparent simplicity of construction and operation, its operative parts being but few and those subjected to wear being capable of interchangeability when necessary.

With these foremost objects in view, the invention has further reference to its salient features of construction and operation of parts, as well as certain other objects, and advantages not heretofore set forth, which will be manifested in the following detail description and illustrated in the accompanying drawings, wherein:

Figure 1 represents a side elevational view of the invention in operative position within a well, shown in axial cross-section, and

Figure 2 is a side elevational view in a similar position.

Proceeding now more in detail with the drawing, it may be first stated for the purpose of setting out in a comprehensive manner the specific improvement contemplated, that heretofore, when a driller encounters what appears to be "pay sand" he is first required to pull the drill pipe assembly, re-enter the hole with a smaller bit to create a shoulder therein to support a string of casing, which is in turn run into the hole. The

drill pipe is then used for washing the sand, and during the process of making such a test, the drill pipe assembly is required to be removed in order to bail out the well. A tubing assembly is usually substituted for the drill pipe, having a working barrel attached in which is contained a valve assembly. In addition to the equipment described, the usual sucker rod assembly is necessary to pump the fluid to the ground surface for a test. Should the test prove of no consequence, drilling to a greater depth must be resumed.

Referring now particularly to Figure 1 of the drawings, the invention is shown as being provided with a valve casing 1 externally threaded to the head 2, which, in turn is threaded to the drill stem assembly, not shown.

The valve casing 1 is provided with interior threads near its lower end for the purpose of supporting the valve head 3, through which slides the valve stem 4, the latter having a central flange 5 into which is threaded the ends of a series of connecting pins 6. These pins pass unrestrictedly through the valve stem guide 7, and while the latter is shown as a single piece, it is of course apparent that its reduced lower end may be detachable if desired to simplify assembly.

As apparent in Figure 1, the valve stem 4 is supplied with expansion rings 7^a for the purpose of maintaining a constant friction on the inner surface of the valve head 3, to take up all possible wear, and further to provide for the substitution of parts should the wear render the same impractical for further use. Moreover, the top of the valve stem 4 is inwardly deflected as a precaution against the accumulation of sand or other such substance thereabove.

The pins 6 are bolted at their lower ends to a bushing 8 surrounding the lower end of the valve guide 7. Interposed between the shoulder *a* of the valve guide 7 and bushing 8 is a compressible annular cushion 9, to which reference will be later made during a description of operation.

Surrounding the bushing 8 is a conical shaped member 10, composed preferably of fiber, or an equivalent material of tough consistency and capable of considerable hard usage, since this member is subjected to great strain. The cone 10 is held against displacement by a coupling 11, threaded upon the

lower end of the valve guide 7, and further provides a connection for the perforated sections of pipe or anchor 12.

In operation, a shoulder *b* is formed in 5 the hole, usually by the use of a small drill bit, after which the invention is substituted for the drill bit by screwing the neck 13 therein, much in the same manner as a drill bit. The tool is then lowered into the hole 10 until the cone 10 strikes the shoulder *b*.

The resiliency of the cone together with the yieldability of the earthen shoulder *b* forms a packing practically impenetrable by the fluid and sand below the shoulder.

15 The entire weight of the drill stem assembly is imposed upon the tool, and consequently upon the cone 10, forcing the latter upward against the enlargement of the bushing 8 to compress the cushion 9, which is 20 caused to seek space beyond the periphery of the tool body, and the fluid, if any, rising by reason of an improper seating of the cone 10 is constrained against passage by the bulging of the cushion 9 against the well 25 wall. This forms a double packing as a precaution against escape of any fluid above the tool.

Compression of the annular cushion 9, permits the pins 6 to be urged upward by 30 reason of the upward sliding of the cone and bushing, hence causing the valve stem 4 to slide within the valve head 3. The ports 14 in the valve are therefore caused to register with those 15 in the head, consequently 35 creating a free passage for the fluid and sand through the ports in the pipe 12 upward to a level above the valve head, where it is entrapped by an upward movement of the tool, since the weight of the sliding 40 members, aided by the resistance of the cushion 9, is such as to return the cone and valve stem 4 to their normal inoperative positions.

45 The tool may be elevated to the ground surface, and a test made of the sand trapped within the drill pipe above the tool.

Should the test prove the strata to be of no value, it is necessary only to substitute the drill for the invention, lower into the 50 hole and resume the drilling operation, preparatory to another test, without the usual waste of time encountered as hereinbefore set forth.

It will be observed that by the use of the 55 sliding valve 4, adherence of substances to the walls of the valve head is positively prevented, which might otherwise render the valve inoperative for the purposes intended as in most types of valves used in a similar 60 manner. This feature is augmented by reason of the deflected upper end of the valve stem. The valve stem is further rendered leak proof, as a preventive against seeping back into the hole the fluid entrapped above 65 the valve, by the interpositioning of packing

rings intermediate and on either side of the valve ports, as shown.

Manifestly, the construction shown is capable of considerable variation, and such variation as is in keeping with the appended 70 claims is considered within the spirit of the invention.

I claim:

1. A sand testing tool including a body containing a valve head and a sliding valve 75 therein, each having ports adapted to register; a relatively stationary guide for said valve; a conical seating member below said valve and operatively connected therewith; an annular compressible cushion intermediate said valve and seating member to yield to the movement of the latter to register said ports, and means to permit passage of fluid through said ports to be trapped above the valve when closed.

2. A sand testing tool including a valve head and sliding valve confined within a casing, each having ports; a conical seating member below said casing arranged to restrict the passage of fluid exteriorly of the 90 latter, and operably connected with said valve; a compressible cushion disposed intermediate said valve and seating member 95 adapted to yield to the movement of the latter when seated to register said ports, and means to permit ingress of sand and fluid to thereby entrap the same above said valve.

3. A well testing tool including a valve head and sliding valve confined within a casing, each having ports; a conical seating member below said casing capable of limited movement relative thereto and having operable connection with said valve; a compressible member intermediate said valve and seating member yielding to the action of 100 the latter when seated to align the ports in said valve head and valve, and means to permit the ingress of fluid into said tool 105 to be trapped above said valve when released.

4. A well testing tool including a valve head and valve confined within a casing, each having ports capable of alignment; a seating member below said casing having operable connection with said valve and arranged to move when seated to effect alignment of said ports; a compressible member 115 interposed between said valve and seating member adapted to yield to the movement of the latter when seated, and means to permit of the entrance of fluid to permit the same to pass above the valve and be thereby trapped when the valve is released.

5. A well testing tool comprising a valve head and valve, each having ports capable of alignment; a movable seating member having operable connection with said valve whereby to actuate the same to effect alignment of said ports when moved; a compressible member arranged intermediate 125 130

said valve and seating member to yield to member being substantially cone shaped; the movement of the latter, and a perforated fluid receiving pipe below said seating member.

- 5 6. An apparatus of the character described including a relatively stationary valve head and a sliding valve having alined ports; a member below said valve capable of limited movement and operably connected with said valve; the body of said

15 member being substantially cone shaped; means to cause upward movement of said member to aline the ports in said valve head and valve, and means to permit the passage of fluid through said ports to entrap the same above said valve when the latter is closed.

In testimony whereof I affix my signature.

CONRAD T. NEITZEL.
